UNITED STATES PATENT OFFICE.

ROBERT ANDERSON, OF CINCINNATI, OHIO.

CONCRETE STRUCTURE.

1,009,712.

Specification of Letters Patent. Patented Nov. 28, 1911.

Application filed January 18, 1911. Serial No. 603,205.

To all whom it may concern:

Be it known that I, ROBERT ANDERSON, a citizen of the United States of America, and resident of Cincinnati, county of Hamilton, 5 and State of Ohio, have invented certain new and useful Improvements in Concrete Structures, of which the following is a specification.

This invention relates to concrete structures, and has for an object to produce a floor structure which may be formed between and be supported from concrete columns, steel columns, combination steel and concrete columns, or any other kind of column which is provided with floor supporting brackets.

An object of my invention is a flat floor construction of reinforced concrete wherein the reinforcing members do not in use become separated from the concrete.

Another object of my invention is a floor panel which is adapted to resist greater compressive and shearing stresses, and to provide convenient locations for the conduits 25 of the building.

A further object of my invention is to produce a concrete structure in which the ceilings are flat, and in which means are employed for dispensing with the ordinary form of column cap usually employed.

A further object is to produce a concrete structure in which means are employed for reducing the cost of material and labor.

A further object is to produce a new and 35 improved floor supporting bracket for reinforced concrete columns.

These and other objects I attain in a structure embodying the features herein described, and illustrated in the drawings accompanying this application and forming a part thereof.

Figure 1 is a partial sectional view on the line 1—1 of Fig. 2, and illustrates a concrete structure embodying features of my invention. Fig. 2 is a diagrammatic plan view of column brackets, in connection with reinforcing members of the floor system. Fig. 3 is a perspective view of a floor supporting bracket, which embodies a detail of my invention, and is shown secured in place on the vertical reinforcing members of a column; the column reinforcing members are shown broken away for convenience of illustration.

One of the principal features of my invention is the construction of the floor panels of a concrete structure, and of the means for

supporting the floor panels of the columns. I so form the floor panels that each panel includes a simple flat reinforced slab, which is suspended between adjacent supporting columns, by means of inclined reinforced members, which are supported or swung from shelves or brackets mounted on the columns.

In the drawings, I have shown an improved form of bracket or shelf for supporting the floor panels, and I will first describe the details of construction of the brackets and then of the floor panels.

The concrete columns 4, illustrated in the drawings, are provided with continuous vertically extending reinforcing rods or members 5, which preferably extend from the foundations to the top of the columns; it being understood that the usual means may be employed for splicing short rods together, for the purpose of forming one continuous reinforcing member. The columns shown are each provided with four reinforcing members 5, but it will be understood that any desired number may be employed, without departing from the scope of my invention.

Each bracket 6 illustrated, consists of concentric octagonal bands 7 and 8 and bracket rods 9. The band 7 of each bracket surrounds and contacts with the reinforcing members 5 of the column and may, if desired, be supported on collars 10, which are mounted on the members 5. The band 8 of each bracket is supported by the bracket rods 9 and is preferably so located that its sides are parallel to the corresponding sides of the band 7. Each bracket rod 9 is bent into U-shaped loops 11—11, and is bent around one of the vertical members 5 immediately above the band 7. Each loop 11 of the bars extends around the band 8, and the apexes of the loops are located approximately at the centers of the sides of the bands. Adjusting or tightening wedges 12 are located between the apexes of the loops and the band 8, and are employed in adjusting the tension in the bars 9 and in adjusting the position of the band 8. The turned or lower ends of the rods 9 project into apertures provided in the collars 10 and in this manner are held firmly in place. If the collars 10 are not employed, the lower ends of the rods may abut against the member 5, around which the rod is bent. The collars 10 are secured in place on the mem-

bers 5 by means of set screws 13 and firmly hold the rods in place, since the eccentric loading on the rods, relative to the collars, causes the collars to bind on the members 5 and to firmly grip the members. Both of the bands 7 and 8 are employed in supporting the floor slabs, or in supporting reinforcing members 15 of the floor slabs. Each reinforcing member 15 is bent so that it 10 forms a horizontal reinforcing member for a floor slab 16 and two inclined supporting members for the slab, which are supported at or near their ends on the brackets 6, at points considerably above the panels. The 15 horizontal portion of each member 15 is located near the bottom of the slab 16, and the inclined portions are either bent at their ends to engage one or the other of the bands 7 or 8, or are continuous and extend across 20 the shelves 6 and through adjacent floor slabs. With this arrangement, the individual reinforcing members 15 may be grouped into three divisions, if desired; those which are secured to the bands 8 of adjacent brackets; those which are secured to the bands 7; and those which are supported by adjacent brackets, but extend over the brackets and through adjacent floor slabs. The members 15 secured to the brackets are turned either 25 up or down to form hooks 17, which engage the bands 7 or 8, and the members are so spaced on the brackets that adequate space is provided for securing them in place, and also for sufficient concrete to insure the monolithic connection between the floor panels 30 and the columns. Each member 15 transmits a portion of the weight of the floor slab and the weight carried by the floor slab, to the supporting brackets, and consequently to 35 the columns.

The central portion 16 of the floor panel is proportioned as though it were a simple reinforced concrete slab supported at points coincident with the meeting points of the 45 horizontal and inclined portions of the reinforcing member 15, and designed to carry such loads as are expected will be located between said points on the panel. The structural or strain-resisting concrete 20 may be 50 reduced in thickness between said points, and so as to leave a channel or aisle between the thicker concrete 21, which surrounds the inclined portions of member 15. This channel provides a convenient location for water 55 and gas pipes 19 and 18, and for electric wires, etc. By making a horizontal portion in member 15, I increase the inclination to the horizontal of inclined portions of members 15, and hence reduce the tension in said 60 portions due to suspending the loads upon the slab, and likewise decrease any tendency of the reinforcing member to change its form under stress and to separate from the inclosing concrete. The aisles may be filled 65 up to the level of the thicker portion of the

floor panels with any suitable material, such as dry cinders, hollow tile, wood or less expensive grades of concrete than that used in the other portions of the structure.

With this arrangement, the cheaper filler 70 is substituted for the concrete, and the heavy column caps employed in concrete structures are done away with and a flat ceiling 75 is obtained. In addition to this, the members 15, which extend across the brackets 6 80 and through the columns, as well as those which are secured to the brackets adjacent to the columns, assist in strengthening the cantaliver brackets, so that the points of suspension of the members 15 can be located 85 at relatively great distances from the centers of the columns, without increasing the thickness of the floor panels. Where the aisles are filled with a substantial filler, such, for example, as concrete, the filler acts in 90 compression and adds strength to the structure.

In Fig. 2, I have illustrated four supporting brackets 6 and the arrangement of the members 15 between the brackets. It 90 will be apparent that the members 15 are so arranged that each bracket co-operates with adjacent brackets in supporting the floor slabs. It will also be apparent that providing octagonal bands 7 and 8, that all 95 of the members 15 extending between adjacent brackets may be of equal length, that is, all the members extending between bands 8 of adjacent columns are of the same length, and all of the members extending between 100 bands 7 of adjacent columns are of one length. The bands 7 and 8 may be made circular, if desired, but with such a construction, the members 15 extending between adjacent brackets will have to be of unequal 105 lengths to accommodate the variations due to the curvature of the bands.

The construction of the brackets is such that their widths may be proportioned in accordance with the distances between columns, so that every portion of each floor panel will be included within the mesh work 110 of reinforcing members; and so that there will be no point between the columns, at which the panel is not sufficiently reinforced, 115 by tension members to withstand the prospective loads.

What I claim is:—

1. In a concrete structure the combination 120 of a column comprising vertical reinforcing members, brackets secured to the reinforcing members, and a floor panel comprising a central comparatively thin slab and thick 125 portions located between the slab and the columns, the slab being below the brackets and comprising horizontal reinforcing members and concrete embedding said horizontal 130 reinforcing members, and the thick portions of the panels comprising inclined reinforcing members connecting the brackets and

the horizontal reinforcing members and concrete embedding said inclined reinforcing members.

2. In a concrete structure, the combination of columns having slab-supporting brackets, floor panels comprising comparatively thin slabs located between the columns and thick portions located between the slabs, and the columns, the slabs being located below the level of the brackets and comprising tension members and concrete embedding said tension members, and the thick portions comprising inclined tension members connecting the column brackets and the tension members of the slab and concrete embedding the inclined tension members.

3. In combination with a concrete column and its vertical reinforcing members, a bracket comprising the following members, viz: an octagonal band mounted on said members, a second octagonal band, bracket rods mounted on said members for supporting said second band, and adjusting wedges

located between said rods and said second band.

4. In combination with a concrete column and its vertical reinforcing members, bracket rods mounted on said members, a band mounted on said bracket rods, and means between said band and said rods for adjusting the position of said band.

5. In combination with a concrete column and its vertical reinforcing members, a bracket comprising the following members, viz: an octagonal band surrounding and connecting with said members, bracket rods turned around the individual members and looped to include a second octagonal band, a second octagonal band, wedges between said second band, and the loops of said rods and collars mounted on said members for securing the ends of the rods in place.

ROBERT ANDERSON.
